UNITED STATES PATENT OFFICE.

FRANK E. RICH, OF CHICAGO, ILLINOIS, ASSIGNOR TO MIEHLE PRINTING PRESS AND MFG. CO., OF CHICAGO, ILLINOIS, A CORPORATION OF ILLINOIS.

GRIPPER MECHANISM.

1,384,778.

Specification of Letters Patent. Patented July 19, 1921.

Application filed April 26, 1919. Serial No. 292,904.

To all whom it may concern:

Be it known that I, FRANK E. RICH, a citizen of the United States, residing at Chicago, in the county of Cook and State of Illinois, have invented certain new and useful Improvements in Gripper Mechanism, of which the following is a specification.

This invention relates to gripper mechanism.

10 Grippers as used heretofore in printing presses, while in some cases being detachable, have not been capable of fine adjustment, nor has it been possible to maintain the grippers accurately in adjusted position. 15 If good results are to be had, grippers must be accurately and nicely adjusted and positively maintained in adjusted position, especially when such grippers are arranged in a relatively long row for gripping a single 20 sheet of paper or other material.

Accordingly, one object of my invention is to facilitate the adjusting of grippers and maintaining same in adjusted position.

Another object is to provide easily detachable and adjustable grippers adapted to 25 meet all of the requirements under service conditions.

These and other objects are accomplished by means of the gripper mechanism shown 30 on the accompanying sheet of drawings, in which—

Figure 1 is a side elevation, the rocker shaft being in section, of my improved gripper mechanism;

35 Fig. 2 is a fragmentary plan view of the same;

Fig. 3 is an enlarged sectional view showing the means for adjusting the grippers and maintaining the same in adjusted position; and

40 Fig. 4 is a sectional view showing the preferred embodiment of my invention.

The most common practice is to have grippers mounted upon a circular shaft by 45 clamp means and set screws which do not under all conditions hold the grippers firmly in adjusted position. As a result thereof, the shaft soon becomes grooved and otherwise marked, making it practically impossible to maintain the grippers in adjusted position, even for a short time. In my gripper mechanism, not only are the grippers readily detachable, but it is practically impossible for the grippers to shift accidentally when once set in adjusted or operative

position. By means of this gripper mechanism also a fine adjustment may be made and the grippers maintained in such adjusted position.

Referring to Figs. 1, 2 and 3 of the drawings, it will be noted that I have shown a gripper mechanism used in connection with a cylinder 10, said gripper mechanism including a shaft 11, capable of the usual rocking motion for opening and closing the grippers proper. This shaft 11 along its length is provided with a projection 12 by cutting associated longitudinally extending V-shaped grooves 13 and 14 in said shaft, the sides of the groove preferably being at an angle of 90° with respect to each other. The sides 15 and 16 of the projection 12 are straight, while the top 17 of the projection preferably is in the arc of a circle, the radius of which is the same as that of the shaft 11. The grippers 18 (only one of which is here shown), which are secured to the shaft, are provided with transverse grooves 19. The bottom 20 of the groove 19 in each case preferably is straight and bears upon the curved surface 17 of the projection 12, whereby the gripper 18 may rock upon the projection when being adjusted. The sides 21 and 22 of the gripper groove 19 preferably are straight and are at a greater angle than 90° with respect to the bottom 20 of the groove to permit a rocking action of the gripper on the projection 12. At the same time, the corners 23 and 24 always engage with sides 21 and 22 respectively of the groove 19 to assist in holding the gripper 18 in adjusted position. The projection 12 is held in the groove 19 and the gripper 18 in each case secured to the shaft 11, preferably by a U-shaped clamp 25, the intermediate portion of which embraces the shaft 11 and the ends of which pass through apertures 26 and 27 in the gripper 18, the ends of said clamp being threaded for receiving nuts 28 and 29 respectively.

As shown in Fig. 1, and as shown in full lines in Fig. 3, the gripper 18 is in its central position with respect to the shaft projection 12, the corners 23 and 24 of the projection 12 engaging the sides 21 and 22 respectively of the groove 19, the nuts 28 and 29 being tightened for maintaining the gripper in adjusted position. As shown in dotted lines in Fig. 3, the gripper 18 has

been rocked on the curved projection surface 17 into an other position with respect to the shaft projection 12. This adjustment is accomplished by tightening one of the 5 nuts 29 and, if necessary, loosening the other nut 28 a corresponding amount. During this adjustment, the gripper 18 rocks on the shaft projection 12, the corners 23 and 24 of the shaft projection 12 at all times remaining in engagement with the sides 21 and 22 of the groove 19. In this way the active gripping end of the gripper which engages the paper, or other material, may be adjusted with great precision and maintained 15 in such adjusted position. At the same time, the gripper 18 cannot shift bodily around the shaft because of the coöperation between the shaft projection 12 and the groove 19. The grippers are readily detachable from the shaft 11 by merely withdrawing the nuts 28 and 29.

The preferred embodiment of my invention is shown in Fig. 4. In this arrangement the shaft 30 is provided with a longitudinally extending V-shaped groove 31, which receives a depending projection 32 on the gripper 33. The converging sides of the projection 32 are at a smaller angle with respect to each other than the sides of the 25 V-shaped groove 31, so that the projection 32 may be rocked within the groove 31 to permit adjustment of the gripper 33 on the shaft 30. The outer end of the projection 32 is rounded to prevent any binding action, 30 but at the same time portions of the projection engage the sides of the V-shaped groove in a positive manner for positive holding purposes. As in the other arrangement, a U-shaped clamp 34 embracing the 35 shaft 30 secures the gripper to the shaft in adjusted position by nuts 35 and 36 engaging the threaded ends of said clamp.

It is my intention to cover all modifications of the invention falling within the 40 spirit and scope of the following claims.

I claim:

1. In gripper mechanism, the combination of a support having a groove, and a gripper having a projection coöperating 50 with said groove in a manner whereby the gripper is rockably adjustably mounted on said support.
2. In gripper mechanism, the combination of a support having a groove, a gripper 55 having a projection coöperating with said

groove in a manner whereby the gripper is rockably adjustably mounted on said support, and means for maintaining said gripper in adjusted position.

3. In gripper mechanism, the combination of a support, and a gripper, said support and gripper having a tongue and groove connection in which the tongue engages a wall of the groove and is arranged in a manner whereby the gripper may be 60 rockably adjusted upon said support.

4. In gripper mechanism, the combination of a support, a gripper, said support and gripper having a tongue and groove connection in which the tongue engages a 70 wall of the groove and is arranged in a manner whereby the gripper may be rockably adjusted upon said support, and means for securing the gripper in adjusted position.

5. In gripper mechanism, a rockable support having a groove, and a gripper having a projection extending into said groove and having a portion engageable with a wall of 80 said groove in a manner whereby the gripper may be rocked on said support for adjustment purposes.

6. In gripper mechanism, a rockable support having a groove, a gripper having a projection extending into said groove and having a portion engageable with a wall of 85 said groove in a manner whereby the gripper may be rocked on said support for adjustment purposes, and means for securing the gripper in adjusted position.

7. In gripper mechanism, the combination of a shaft having a groove with straight sides, a gripper having a projection extending into said groove, portions of said projection at all times engaging the sides of 95 said groove, the gripper being adjustable on said shaft, and means for holding said gripper in adjusted position.

8. In gripper mechanism, the combination of a rockable support, and a gripper 100 removably secured to said support, said gripper and support having a tongue and groove connection in which the tongue engages a wall of the groove and is arranged in a manner whereby one may be rockably adjusted with respect to the other.

Signed at Chicago, Illinois, this 18th day of April, 1919.

FRANK E. RICH.
